UNITED STATES PATENT OFFICE.

LOUIS GREEN, OF HOWRAH, CALCUTTA, BRITISH INDIA.

RAIL SUPPORT AND FASTENING.

Application filed March 2, 1921. Serial No. 448,962.

To all whom it may concern:

Be it known that I, LOUIS GREEN, residing at 5 Church Road, Howrah, in the suburbs of Calcutta, British India, a subject of the 5 King of Great Britain, have invented certain new and useful Rail Supports and Fastenings (for which I filed an application in Great Britain May 26, 1920, No. 29,704), of which the following is a specification.

10 This invention refers to improvements in or relating to railway rail chairs or rail supporting means (hereinafter referred to as rail chairs) and in means for holding and securing rails in such chairs and for locking the tiebars in position in the case of sleepers which consists of two blocks or 15 pots connected by a tie-bar to maintain the gauge of the line.

In my previous British patent specifications Nos. 11951/1913, 8514/1914, and 20 8698/1914, I have described certain improvements in reinforced concrete sleepers, and also a special resilient rail-support or chair capable of being used with most types 25 of sleepers, such as those of steel or wood, but particularly applicable to reinforced concrete sleepers.

It is with such resilient chairs or rail-supports and their attachments designed for 30 use with bull-headed rails that my present invention more particularly deals.

In order that my invention shall be fully understood I will describe the same with reference to the accompanying drawings, in 35 which:—

Fig. 1 is a side view of my improved resilient chair designed for use with a bull-headed rail showing the manner of supporting the rail on the chair seat and of securing it in position. The chair itself, it will 40 be seen, is fixed in a concrete block by means of its prongs.

Fig. 2 is a side view of the clip shown in Fig. 1.

Fig. 3 is an end view of the same.

Fig. 4 is a side view of a modified design of the same.

Fig. 5 is an end view of the same.

Fig. 6 is a plan of the chair, rail, and tie-bar, and of the means for interlocking these parts.

Fig. 7 is an end view with the same arrangement of parts grouped and interlocked in their final position as they will appear in 55 the road.

In Fig. 8 the resilient chair illustrated

differs from that shown in Fig. 7 in being fixed on a wooden bed, instead of on a reinforced concrete block.

Fig. 9 is a side view of a clip modified to 60 suit this type of chair.

Fig. 10 is an end view of the same showing the tongue that fits in a slot in the chair base.

Figs. 11 and 12 show a modification of the 65 same.

Fig. 13 is a plan of the assembled parts illustrated in Fig. 8.

Fig. 14 is an end view of the same.

Referring particularly to Figs. 1 to 7:— 70 1 and 2 in Figs. 1, 6, and 7, represent one type of resilient chair, in which 1 is the rail seat and 2 the shoulder against which the rail rests.

3 is a double humped cotter for locking 75 the tie-bar in place.

4 is the head of the bolt shaped to fit the curve of the clip so as not to turn.

5 is a thin washer the ends of which are bent over the tie-bar after the nut has been 80 tightened on the bolt.

6^a is a clip whose top end is in contact with the web of the rail.

6 is the line of contact between the clip and the rail.

7 is the line of contact between the shoulder of the chair and the web of the rail.

6 being below 7 the rail is pressed against the side of the chair and held in its seat, the clip 6^a engaging with and locking the 90 tie-bar in the chair, the end of the tie-bar being further locked in the chair by means of the bent cotter 3.

Referring now more particularly to Figs. 8 to 14:— 95

8 is a wooden block or sleeper which replaces the reinforced concrete slab 3^a illustrated on sheet 1.

9 and 10 are the extremities of the chair bent horizontally to form a suitable base 100 for resting upon the bed or foundation on the wooden block or sleeper to which it is attached.

11 is one of the rail screws which fix the chair to its bed. Dog spikes or bolts might 105 be used with equal advantage.

12 is a projection on the lower end of the clip.

13 is a slot in the chair base into which 110 12 fits and locks.

In the constructions shown in Figs. 8 to 14;

The extremities 9 and 10 of the legs of the chair are bent outwards and horizontally to form a base, and holes are punched or drilled in each base 9 and 10 for attaching the chair to its bed 8 by means of rail-screws such as 11 or spikes or bolts. It will be seen from the illustration in this case the clip holds the rail at one end and engages with the slot 13 in the base of the chair itself and not with a tie-bar as in Fig. 1.

In one of my said prior British patent specifications, viz. No. 8698 of 1914, I described a resilient chair in which the rail is carried in a bent metal stirrup or loop and wedged in place by a wooden or a metal key. In the same specification I further described a resilient chair designed for carrying flat-footed rails. I now propose to combine those two types in such a manner as to form a composite chair representing half of one type and half of the other. The object of this combination is (inter alia) to reduce the weight and cost of the chair and eliminate the bending moments near the junction of the legs of the chair and the concrete, also to reduce the bending moments in other parts of the chair, particularly in the stirrup. The angles of the legs being functions in the equation which determines the bending moments in the chair, it is possible by giving suitable values to the angles, to reduce all bending moments to a minimum.

In combination with this chair 1, 2, I propose to use a clip such as shown in Figs. 1 to 3, Figs. 4 and 5, Figs. 9 and 10 or Figs. 8, 11 and 12, and this clip is prolonged and carried upwards along the web of the rail to a point 6 just below the point of contact 7 between the rail web and the jaw of the chair on the opposite side of the rail. The functions of this clip are to hold and lock the tie-bar on the one hand when a tie-bar is used and to secure and hold the rail in the chair on the other. The clip 6^a itself is fitted and attached to the chair by means of a bolt 4 and nut passed through corresponding holes in the clip 6^a and in the chair seat 1. By tightening the nut on the said bolt 4 the clip is pressed against the web of the rail, and the rail against the jaw of the chair.

It is obvious that this action is automatically repeated by the depression of the rail when a train is passing over it, and the effect is to hold the rail firmly and to reduce creep. Normal expansion and contraction of the rail due to variations of tem-

perature is not affected by this arrangement.

What I claim is:—

1. A resilient rail-support or chair, for bull-headed or double-headed rails, for use with sleepers of railways tramways and the like; such rail-support or chair having a horizontal portion located above and clear of the sleepers and adapted to form a seating for the bottom of said rail and having one end of said horizontal portion extending directly from said horizontal portion downwardly and outwardly at an obtuse angle to form one outwardly inclined leg or member adapted to be secured to the sleeper, and having the other end of said horizontal portion extending directly from said horizontal portion upwardly and inwardly i. e. at an acute angle to said horizontal portion so as to be adapted to bear against the web of the said rail when the latter is positioned in said chair, and thence curved outwardly upwards and then extending downwardly to form the other leg or member inclined oppositely to the first-named leg and adapted to be secured to the sleeper substantially as described.

2. A resilient rail-support or chair as claimed in claim 1 herein, a tie-bar to maintain the gauge of the line, slots in the legs of said chair to receive and engage with said tie-bar, a metal plate or clip—having a right-angled portion—one limb of which is adapted to fit against and support the web of the rail, the other limb being provided with a notch adapted to fit over the edge of the tie-bar and means to secure said clip in position.

3. A resilient rail-support or chair such as claimed in claim 1, a tie-bar to maintain the gauge of the line, slots in the legs of said chair to receive said tie-bar, notches in the lower edge of said tie-bar to engage the edge of said slots, a bent metal plate or clip having a right-angled portion, one limb of which right-angled portion is adapted to fit against the web of the rail and the other limb being provided with a bolt hole through which a bolt can be passed through the horizontal portion of the chair and a curved extension or prolongation of this last-named limb curved in the opposite direction to the first-named limb and provided with a notch adapted to engage the upper edge of the tie-bar substantially as described.

L. GREEN.
